UNITED STATES PATENT OFFICE.

BARNETT BECKENSTEIN, OF BROOKLYN, NEW YORK.

DESIGN FOR A SWEATER.

Application filed May 22, 1922. Serial No. 2,364. Term of patent 3½ years.

To all whom it may concern:

Be it known that I, BARNETT BECKENSTEIN, a citizen of the United States, residing at No. 597 De Kalb Avenue, in the borough of Brooklyn, county of Kings, city and State of New York, have invented a new, original, and ornamental Design for Sweaters, of which the following is a specification, reference being had to the accompanying drawing, forming part thereof.

The figure indicates a front view of my sweater, showing my new design.

I claim:—

The ornamental design for a sweater, as shown.

BARNETT BECKENSTEIN.
